UNITED STATES PATENT OFFICE

MILLS ROGER SNYDER, OF SAVANNAH, GEORGIA, ASSIGNOR TO THE UNION SWITCH & SIGNAL COMPANY, OF SWISSVALE, PENNSYLVANIA, A CORPORATION OF PENNSYLVANIA

RAILWAY BOOTLEG

Application filed August 20, 1929. Serial No. 387,126.

My invention relates to railway bootlegs, that is, to devices for connecting electric conductors with the track rails of a railway, for use in railway signaling and automatic train control.

I will describe several forms of bootlegs embodying my invention, and will then point out the novel features thereof in claims.

In the accompanying drawings, Fig. 1 is a view, partly in elevation and partly cross-sectioned, showing one form of bootleg embodying my invention. Fig. 2 is a top plan view of a portion of the bootleg shown in Fig. 1. Fig. 3 is a side elevation of a portion 15 of the bootleg shown in Fig. 1. Fig. 4 is a sectional view showing a modified form of bootleg, embodying my invention. Fig. 5 is a top plan view of the bootleg shown in Fig. 4. Fig. 6 is a bottom view of a contact member forming a part of the bootleg shown in Fig. 4. Figs. 7 and 8 are top and bottom views, respectively, of another contact member forming a part of the bootleg illustrated in Fig. 4. Fig. 9 is a view, partly in elevation and partly cross-sectioned, showing another modified form of bootleg, also embodying my invention. Fig. 10 is a view, showing in side elevation, a portion of the bootleg illustrated in Fig. 9. Fig. 11 is a bottom view of a contact member forming a part of the bootleg shown in Fig. 9. Fig. 12 is a view, partly in elevation and partly cross-sectioned, showing still another modified form of bootleg, also embodying my invention.

Similar reference characters refer to similar parts in each of the several views.

Referring first to Figs. 1, 2 and 3, the bootleg comprises a suitable housing such as a concrete structure 1, the lower end of which will be embedded in the ground, and the upper end of which will project above the surface of the ground. As here shown, the structure 1 is tapered toward its top, and is provided with a vertically extending centrally located hole 2 through which an insulated conductor 3 is brought up from the ground.

Mounted on the upper end of the structure 1 is a top plate 4, preferably of metal, having

two integral lugs 4^a and 4^b, as best seen in Fig. 2. The lug 4^a is provided with a vertically extending hole 4^c, and the lug 4^b is provided with a similar hole 4^d. Extending upwardly through the holes 4^c and 4^d are two studs 5, the lower ends of which are anchored in the concrete structure 1, and the upper ends of which are threaded to receive nuts 5^a by means of which the top plate is securely fastened to the structure 1. 55

The top plate 4 carries a terminal structure designated, in general, by the reference character A. As here shown, the terminal structure A comprises a terminal post 6, the shank 6^a of which passes through a vertically extending centrally located hole 4^c in the top plate 4, but which is insulated from the top plate 4 by a bushing 14 of suitable material, such as fiber, and by two insulating washers 15 and 16 which fit snugly over the ends of the bushing on opposite sides of the top plate 4. An annular shoulder 6^b, integral with the terminal post 6 on the upper side of the top plate 4, engages the upper face of the insulating washer 16, so that when a nut 17 is screwed onto the lower end of the shank 6^a is tightened, the terminal post is securely clamped to the top plate 4. Interposed between the nut 17 and the insulating washer 15 is a lock washer 19 and a plain washer 18. 60 The plain washer 18 distributes the pressure evenly over the insulating washer 15 while the lock washer 19 prevents the nut 17 from working loose due to vibration. 70

The lower end 6^c of the terminal post 6 has a smaller diameter than the shank 6^a of the terminal post and is threaded to receive nuts 20. (See Figs. 1 and 3). The insulation is removed from the upper end of the conductor 3, and the exposed end 3^a of the conductor 3 is coiled around the end 6^c of the terminal post 6 between the nuts 20 and the shank 6^a so that when the nuts 20 are tightened the conductor 3 is electrically connected with the terminal post. 80

The upper end of the terminal post 6 is provided with an elongated head 6^d which is inclined at an angle with the horizontal as best seen in Fig. 3. This head is provided with an axial opening 6^e adapted to receive the end 90

of a rail connector 10 whereby the terminal post may be electrically connected with a track rail which is not shown in the drawing.

For securing the connector 10 in place in the terminal post 6 and for insuring good electrical connection between the terminal post and the rail connector 10, two set screws 8 and 9 are screwed through spaced threaded holes 6^a and 6^b in the left hand side of the head 6^a, as viewed in Figs. 1 and 2, and a similar set screw 7 is screwed through a threaded hole 6^b in the right hand side of the head. The set screws 7, 8 and 9 each engage the connector 10, and are provided with lock nuts 13, 12 and 11, respectively, which prevent the set screws from working loose after they are tightened.

Referring now to Figs. 4 to 8, inclusive, I have here shown a top plate 21 which is similar to the top plate 4 illustrated in Fig. 1, and which may be attached to the structure 1 in the same manner as described in connection with the top plate 4 in Fig. 1. The top plate 21 carries a terminal structure B comprising a lower contact member 22 and an upper contact member 23. The lower contact member 22 is provided with two holes 22^a and 22^b which are coaxial with two holes 21^a and 21^b, respectively, in the top plate 21. Extending upwardly through the holes 21^a and 22^a is a bolt 24, and extending upwardly through holes 21^b and 22^b is a similar bolt 25. A nut 24^a is screwed on the bolt 24 above the contact member 22 and is prevented from working loose by a lock washer 30 interposed between the nut and the contact member. A similar nut 25^a is likewise screwed on the bolt 25 above the contact member 22 and is locked in place by a lock washer 31 interposed between the nut and the contact member. An insulating sleeve 26 surrounds the shank of the bolt 24 where it passes through the top plate 21, and a similar insulating sleeve 27 surrounds the shank of the bolt 25 where it passes through the top plate 21. An insulating washer 28 located between the top plate 21 and member 22 is provided with holes which receive snugly the upper ends of sleeves 26 and 27. A similar washer 29 is located on the under side of the top plate 21 and fits snugly over the lower ends of the sleeves 26 and 27. The insulating sleeves and insulating washers insulate the lower contact member from the top plate 21.

The contact member 22 is also provided, on its lower face, with a projection 22^c, and on its upper face with a transverse ridge 22^e. As best seen in Fig. 8, the projection 22^c is cylindrical, and this projection extends downwardly through a hole 21^c in the top plate 21 and through suitable holes in the insulating washers 29 and 28. The contact member 22 is further provided with a hole 22^d which extends vertically through the ridge 22^e and the projection 22^c, and which

is adapted to receive a terminal post 36. The portion of the hole 22^d which extends upwardly through the ridge 22^e is square, as best in Fig. 7, and engages the head of the terminal post 36 to prevent the terminal post from turning with respect to the contact member 22. A nut 38 screwed on the lower end of the terminal post 36 clamps the terminal post to the contact member 22. The exposed upper end 3^a of the conductor 3 is twisted around the terminal post 36 between two washers 39 and is fastened to the terminal post by means of two nuts 37, to provide electrical connection between the conductor 3 and the contact structure B.

The upper contact member 23 is mounted on the upper ends of the bolts 24 and 25, and is provided with holes 23^a and 23^b, which receive the bolts 24 and 25, respectively. The contact member 23 is provided in its lower face with a transverse groove 23^d (see Fig. 6) which aligns with a similar groove 22^f formed in the upper face of the ridge 22^e. The grooves 23^d and 22^f form an opening which receives the rail connector 10. Two nuts 24^b and 25^b screwed, respectively, on the upper ends of the bolts 24 and 25, above the contact member 23, clamp the contact member 23 against the connector 10 with considerable force to secure good electrical contact between the connector and the contact members. A lock washer 32 is interposed between the nut 24^b and the contact member 23, and a similar lock washer 33 is interposed between the nut 25^b and the contact member 23 to prevent the nuts 24 and 25 from working loose. A set screw 34 is screwed through the member 23 into engagement with the connector 10. A jam nut 35 on the set screw 34 prevents the set screw 34 from working loose after the set screw has been tightened.

Referring now to Figs. 9 to 11, inclusive, the modified form of bootleg here shown comprises a terminal structure C mounted on a top plate 40 similar to the top plate 4 shown in Fig. 1. The terminal structure C comprises a terminal post 41 provided with a shank 41^a, which extends through the top plate 40, and a shoulder 41^b located above the top plate 40. The shank 41^a is threaded (see Fig. 10) and receives the nut 17, by means of which the terminal post is fastened in place. For convenience in holding the terminal post 41 while the nut 17 is being tightened, the shoulder 41^b is made hexagonal. The terminal post 41 is insulated from the top plate 40 by an insulating bushing 14^a and insulating washers 15^a and 16^a which are similar to the insulating bushing and insulating washers by means of which the terminal post 6 in Fig. 1 is insulated from the top plate 4. The lower end 41^c of the terminal post 41 has a smaller diameter than the shank 41^a of the terminal post and is threaded to receive the nuts 20 which electri-

cally and mechanically fasten the conductor 3 to the terminal structure. The upper end 41^a of the terminal post is provided with a transverse opening 41^b, (see Fig. 10), which terminates at each end in a semi-circular groove formed in the upper face of the shoulder 41^b. The connector 10 extends through the opening 41^b and is engaged at its upper side by a contact member 42 which fits loosely over the terminal post and which, as best seen in Fig. 11, is provided with a transverse semi-circular groove 42^a adapted to align with the groove in the upper face of the shoulder 41^b. A nut 44 screwed on the upper end 41^a of the terminal post, clamps the contact member 42 against the connector 10 with considerable force to provide good electrical connection between the connector and the terminal structure. A lock washer 43, interposed between the nut 44 and member 42, prevents the nut from working loose. To insure good connection between the terminal structure and the connector 10, a set screw 45 is screwed into engagement with the connector 10 through a threaded axial hole 41^c in the upper end of the terminal post 41.

Under some conditions, it is desirable to bring the conductor 3 up from the ground through a pipe 47 as shown in Fig. 12 instead of through the concrete structure 1 as shown in Fig. 1. Under these conditions, the terminal structure, here shown as the terminal structure C, of Fig. 9, may be mounted on a top plate 46 which is provided with a downwardly turned flange 46^a carrying a set screw 48. The top plate 46 and flange 46^a form a cap which fits over the top of the pipe 47 in a manner which prevents moisture from entering the pipe. It will be apparent that when the set screw 48 is tightened, the top plate 46 is securely fastened on top of the pipe 47.

One advantage of a bootleg embodying my invention is that due to the large contact surface which is provided between the rail connector 10 and the terminal structure good electrical connection between the connector and the terminal structure is insured.

Another advantage of a bootleg embodying my invention is that the mechanical connection between the rail connector and the terminal structure is rigid and the parts are constructed in such manner that they will not become loosened due to vibration.

Still another advantage of a bootleg embodying my invention is that all adjustments of the parts may be made with an ordinary wrench, and no special tools are required.

Although I have herein shown and described only a few forms of bootlegs embodying my invention, it is understood that various changes and modifications may be made therein within the scope of the ap-

pended claims without departing from the spirit and scope of my invention.

Having thus described my invention, what I claim is:

1. A bootleg for connecting an electric conductor with a rail connector, comprising a housing projecting upwardly from the ground and enclosing said conductor, a top plate attached to said housing, a terminal structure extending through but insulated from said top plate and clamped to said top plate and provided with an opening to receive the rail connector and with means for electrical connection with the upper end of said conductor, and a set screw extending into said opening for engaging said rail connector to secure said rail connector to said structure and to insure good electrical contact between said structure and said rail connector. 40 75 80 85

2. A bootleg for connecting an electric conductor with a rail connector, comprising a housing projecting upwardly from the ground and enclosing the conductor, a top plate attached to said housing, a terminal post having its shank extending through said top plate and having an annular shoulder located above said top plate and provided with an opening above said top plate adapted to receive said rail connector, a nut screwed on said shank on the underside of said top plate for clamping said terminal post to said top plate, means for insulating said terminal post from said top plate, means integral with said terminal post for fastening the upper end of said conductor with said terminal post, and a set screw in said terminal post engaging said connector for securely fastening said rail connector to said terminal post. 95 100 105

3. A bootleg for connecting an electric conductor with a rail connector, comprising a housing projecting upwardly from the ground and enclosing the conductor, a top plate attached to said housing, a terminal post having its shank extending through said top plate and provided with an annular shoulder above said top plate and with an elongated head above said shoulder and also having a threaded lower end of smaller diameter than said shank, a nut screwed on said shank on the underside of said top plate for clamping said terminal post to said top plate, an insulating bushing surrounding the shank of said terminal post where said shank passes through said top plate, two insulating washers one interposed between said top plate and said shoulder and the other interposed between said nut and said top plate, other nuts screwed on the lower threaded end of said terminal post for fastening the exposed upper end of said conductor to said terminal post, said head being provided with an axial hole adapted to receive a rail connector, three set screws two screwed through one side of said head into said hole and the other screwed 110 115 120 125 130

through the other side of said head into said hole for engaging said rail connector to clamp said connector to said terminal post, and three lock nuts one secured on each set screw for locking said set screws in place.

5 4. A bootleg for connecting an electric conductor with a rail connector, comprising a housing projecting upwardly from the ground and enclosing the conductor, a top plate attached to said housing, a first contact member clamped against the upper side of said top plate but insulated therefrom and having a downward projection extending through said top plate and having a hole 10 extending through said member and said projection, a terminal post extending through said hole and provided on its lower end with nuts for connecting the exposed upper end of said conductor with said first contact member, said first contact member also being provided in its upper face with a groove adapted to receive said rail connector, a second contact member, and means for clamping said second contact member against said rail connector to electrically and mechanically connect said contact members with said connector.

5 5. A bootleg for connecting an electric conductor with a rail connector, comprising a housing projecting upwardly from the ground and enclosing the conductor, a top plate attached to said housing, a first contact member clamped against the upper side of said top plate but insulated therefrom and having a downward projection extending through said top plate and provided with a hole extending through said member and said projection, a terminal post extending through said hole and provided on its lower end with nuts for connecting the exposed upper end of said conductor with said first contact member, said first contact member also being provided in its upper face with a groove adapted to receive a rail connector, a second contact member provided with a groove aligned with the groove in said first contact member, means for clamping said second member against said rail connector to electrically and mechanically connect said two contact members with said connector, and a set screw threaded through said second contact plate into engagement with said connector to hold said connector in place.

5 6. A bootleg for connecting an electric conductor with a rail connector, comprising a housing projecting upwardly from the ground and enclosing the conductor, a top plate attached to said housing, a terminal structure comprising a first contact member having a projection extending downwardly through said top plate, two bolts extending upwardly through said top plate and said first contact member, two insulating sleeves one on each bolt where said bolt passes through said top plate, two insulating wash-

ers one between said first contact members and said top plate and the other between the heads of said bolts and said top plate, two nuts one screwed on each bolt for clamping said first contact members to said top plate, a terminal post extending downwardly through said first contact plate and provided with nuts for connecting the post with the upper end of said conductor, a second contact member mounted on said bolts above said first contact members, said first contact member being provided on its upper face with a ridge having a groove and said second contact member being provided in its lower face with a similar groove which is aligned with the groove in said first member to form an opening for receiving said rail connector, additional nuts on said bolts above said second contact member for clamping said connector between said contact members and a set screw threaded through said second contact member to grip said connector and lock said connector in place.

7. A bootleg for connecting an electric conductor with a rail connector, comprising a housing projecting upwardly from the ground and enclosing the conductor, a top plate attached to said housing, a terminal post having its shank extending through said top plate and having a shoulder located above said top plate and provided with a transverse opening terminating at each end in a groove formed in the upper face of said shoulder, said groove and said opening being adapted to receive said rail connector, a contact member fitting loosely over said terminal post above said rail connector and provided with a groove in its lower face adapted to receive said connector on each side of said post, a first nut screwed on said terminal post above said contact member for clamping said contact member against said connector, a set screw extending downwardly through said terminal post into engagement with said connector to insure good mechanical connection between said connector and said terminal post, a second nut screwed on said shank on the underside of said top plate for clamping said terminal post to said top plate, means for insulating said terminal post from said top plate, and means integral with said terminal post for fastening the end of said conductor to said terminal post.

8. A bootleg for connecting an electric conductor with a rail connector, comprising a pipe projecting upwardly from the ground and enclosing the conductor, a top plate provided with a downwardly turned flange and fitting over said pipe, a first set screw screwed into engagement with said pipe through said flange for fastening said top plate to said pipe, a terminal post having its shank extending through said top plate and having a shoulder located above said top plate and provided with a transverse opening terminat-

ing at each end in a groove formed in the upper face of said shoulder, said groove and said opening being adapted to receive said rail connector, a contact member fitting loosely over said terminal post above said rail connector and provided with a groove in its lower face adapted to receive said connector on each side of said post, a first nut screwed on said terminal post above said contact member for clamping said contact member against said conductor, a set screw extending downwardly through said terminal post into engagement with said connector to insure good mechanical connection between said connector and said terminal post, a second nut screwed on said shank on the underside of said top plate for clamping said terminal post to said top plate, means for insulating said terminal post from said top plate, and means integral with said terminal post for fastening the upper end of said conductor with said terminal post.

In testimony whereof I affix my signature.
M. ROGER SNYDER.
